UNITED STATES PATENT OFFICE.

JOHN KECSKEMETY, OF DETROIT, MICHIGAN.

PISTON.

1,368,938.

Specification of Letters Patent. Patented Feb. 15, 1921.

Application filed February 24, 1919. Serial No. 278,586.

To all whom it may concern:

Be it known that I, JOHN KECSKEMETY, a citizen of the United States of America, residing at Detroit, in the county of Wayne 5 and State of Michigan, have invented certain new and useful Improvements in Pistons, of which the following is a specification, reference being had therein to the accompanying drawings.

10 My invention aims to provide a novel piston for internal combustion engines, and the invention may be characterized in the following particulars.

First, there is a novel piston body that 15 may be made of light and durable metal, as aluminum, so as to contribute to a minimum weight in connection with an engine. The piston body is constructed for attachment to a piston rod or pitman in the usual and well 20 known manner, and said body has provision for rapid cooling and the attachment of a head and packing rings.

Second, my invention includes a detachable piston head adapted to be screwed or otherwise mounted on the piston body and said head has provision for holding packing rings.

The piston head may be made of cast iron or other indurate material capable of with- 30 standing considerable pressure and a high temperature incurred by explosions in an engine cylinder, the head protecting the piston body and thereby increasing the longevity of the same.

35 Third, the piston head includes novel means for retaining piston or packing rings in engagement therewith while placing the head in engagement with the piston body, and a guide ring and spanner wrench are 40 utilized to facilitate assembling the piston head, packing rings and piston body which is accomplished while the piston body is in a cylinder.

Fourth, the detachable piston head is pro- 45 vided with novel means for locking it in engagement with the piston body, and means are provided to prevent the head locking means from becoming accidentally dis- 50 placed or injured during the operation of the piston.

The above and other characteristics of my invention will be more fully understood after considering the mechanical construction entering into the piston, and reference 55 will now be had to the drawing, wherein—

Figure 1 is a vertical sectional view of a

portion of an engine cylinder with a piston body therein, showing the piston head detached and about to be connected to the piston body by utilizing a spanner wrench; 60

Fig. 2 is a vertical sectional view of the piston with the head connected thereto;

Fig. 3 is a plan of the piston head with locking means in position to provide clearance for a spanner wrench, and 65

Fig. 4 is a plan of the piston shown in Fig. 2.

In the drawing, the reference numeral 1 denotes a piston body made of aluminum or other light and durable material. The piston body has the lower end thereof open, and the upper end of said body is reduced to provide an inner head 2 of less diameter than the piston body 1 and the cylindrical wall of the head 2 is exteriorly screw- 70 threaded, as at 3. At the juncture of the head 2 with the body 1 there is an annular groove 4 and an annular shoulder 5, the purpose of which will presently appear. 75

6 denotes an outer head that may be made 80 of cast iron, steel or other indurate material, and this head has an annular wall 7 which is interiorly screwthreaded, as at 8, so that the head 6 may be screwed on the inner head 2 into abutting relation therewith as 85 shown in Fig. 2. The annular wall 7 has a rounded edge 9 adapted to engage in the annular groove 4 and the outer face or periphery of the wall 7 has a peripheral channel or wide groove 10 to receive a plurality 90 of split packing rings 11, which in their extended condition are retained on the wall 7 between the head 6 and the outer end of the wall 7, as shown in Fig. 1. The rounded end 9 of the wall 7 facilitates as- 95 sembling the piston or packing rings 11, and these rings are of a conventional form adapted by their inherent expansive force to snugly engage the walls of an engine cylinder 12 and insure a non-leakable con- 100 nection between the walls of the piston and the walls of the cylinder.

To facilitate mounting the outer head 6 on the inner head 2, two devices may be employed. First, there is a spanner wrench 13 105 having diametrically opposed pins 14 adapted to be placed in sockets 15 in the outer head 6, and said spanner wrench has a cross head or handle 16 which permits of the wrench and the outer head being easily ro- 110 tated. The second device is a guide ring or member 17 which is placed on the end of

the cylinder 12 to form an entrance into the end of the cylinder. The inner wall of the guide ring or member 17 is beveled and this guide member or ring is adapted to retract 5 the packing rings 11 as the outer head 6 is screwed on to the inner head 2 within the cylinder 12. The guide ring or member 17 retracts the packing rings sufficiently to place said rings under compression so that 10 when the outer head is screwed on the inner head the packing rings will frictionally engage the walls of the cylinder 12. After the outer head 6 is in engagement with the inner head 2, and the inner wall of the channel or 15 groove 10 is in a plane with the shoulder 5 of the piston body and the packing rings can readily expand to a diameter greater than that of the piston body or its heads.

To lock the outer head 6 in engagement 20 with the inner head 2 of the piston body, the inner head 2 is provided with an interior enlargement or boss 18 having a socket 19 with the walls thereof screwthreaded. One of the sockets 15 of the outer head 6 is 25 formed with a bottom opening 20 adapted to register with the socket 19, so that a screw 21 may be mounted in the outer head 6 to engage in the socket 19 and hold the outer head against accidental rotation relative to 30 the inner head. The head of the screw 21 occupies a portion of the socket 15 provided for the spanner wrench and it is therefore obvious that the screw 21 must be removed before the spanner wrench can be utilized 35 for rotating the outer head relative to the inner head.

Since there is a possibility of the screw 21 becoming loose, I provide novel means to prevent accidental displacement of said 40 screw, said means comprising a rotary shutter or closure member 23 held by a rivet or other pivotal means 24 in a circular recess 22 provided therefor in the outer head 6, said shutter or closure member having an opening 45 25 adapted to register with the socket 15 which receives the head of the screw 21. With the opening 25 of the shutter or closure member 23 registering with the socket 15 containing the screw 21, the end of the cross 50 head or handle 16 of the spanner wrench 13 may be utilized as a screw driver for removing the screw 21 but when the shutter or closure member 24 is shifted, for instance, as shown in Fig. 4, then it is impossible for 55 the screw 21 to become accidentally displaced. The screw 21 is also protected against excessive heat or any action due to explosions in the engine cylinder 12, and with the outer head 6 of an indurate ma- 60 terial and a greater thickness than the inner head 2, the inner head 2 is well protected with the piston body 1 serving as a skirt or guide member therefor in the cylinder 12.

The inner head 2 may be reinforced by 65 ribs or webs 26 and has suitable provision as at 27, for connection with a piston rod or pitman 28.

The wall 7 of the outer head has its inner 70 end shaped so as to retain the piston rings on the outer head, but when placing these piston rings in engagement with the outer head it is not necessary to expand the same to any great extent, as the rings may be 75 readily slipped on the outer head and temporarily retained thereon by any suitable means, but when it comes to removing the outer head, from the inner head, then the outer head carries the piston rings therewith. This is a distinct advantage in assembling and disassembling the parts of the 80 piston.

It is thought that the utility of my improved invention will be apparent without further description, and while in the drawing there is illustrated a preferred embodiment of my invention, it is to be understood that the structural elements are susceptible 85 to such variations and modifications as fall within the scope of the appended claims.

What I claim is:—

1. A piston comprising a body having the outer end thereof reduced and exteriorly screwthreaded, the reduced end of said piston body providing an annular groove and shoulder, an outer head having an interiorly screwthreaded wall adapted for engagement with the reduced end of said piston body, and adapted to enter the annular groove of said body, packing rings on the wall of said outer head adapted to engage the annular shoulder of said piston body when said outer head is mounted thereon, and locking means for the outer head relative to the reduced end of said piston body and operable from the top of said outer head. 100

2. A piston comprising a body having the outer end thereof reduced to provide an inner head, an outer head mounted on the inner head of said body and provided with sockets, packing rings carried by the outer head, a screw in one of the outer head sockets locking said outer head relative to the inner head of said piston body and adapted to be removed to permit of said sockets cooperating in receiving a tool to remove the outer head, and a closure member carried by said outer head and adapted for protecting said screw, said closure member having an opening adapted to register with the screw socket. 110

In testimony whereof I affix my signature in the presence of two witnesses.

JOHN KECSKEMETY.
